E. F. HARTSHORN.
AWNNG.
APPLICATION FILED FEB. 5, 1913.

1,081,042.

Patented Dec. 9, 1913.

UNITED STATES PATENT OFFICE.

EDMUND F. HARTSHORN, OF NEWARK, NEW JERSEY, ASSIGNEE TO STEWART HARTSHORN COMPANY, OF EAST NEWARK, NEW JERSEY, A CORPORATION OF NEW JERSEY.

AWNING.

1,081,042.

Specification of Letters Patent.

Patented Dec. 9, 1913.

Application filed February 5, 1913. Serial No. 746,283.

To all whom it may concern:

Be it known that I, EDMUND F. HARTSHORN, a citizen of the United States, residing in Newark, county of Essex, and State of New Jersey, have invented a certain new and useful Awning, of which the following is a specification.

This invention relates to awnings for windows and the like.

10 It is an improvement on the awning disclosed in my co-pending application for patent, filed July 1, 1912, Serial No. 706,877.

The objects of the invention are: First: To strengthen the frame, and particularly 15 the spreaders. Second: To improve the connection between the fly-rods and spreaders, so that the latter may be more securely supported and will slide up and down on the fly-rods without jamming. Third: To avoid 20 the use of a chain for supporting the spreaders in open position. These and further objects will more fully appear from the following specification and drawings, considered together or separately.

25 In the drawings, Figure 1 is a front view of an awning embodying my invention in place in a window opening, a portion of the upper part of the awning being open and the lower half furled. Fig. 2 is a side view showing the lower part of the awning extended, in full lines, and furled, in dotted lines. Fig. 3 is a perspective view of the slider on one of the fly-rods. Figs. 4, 5 and 6 are cross-sections taken respectively upon the lines 30 4-4, 5-5 and 6-6, of Fig. 3. Fig. 7 is a front view, on a reduced scale, of a modified form of awning. Fig. 8 is a detail view, of a portion of the device, showing the spring for initially moving the spreaders and Fig. 40 9 is a plan view of the spring.

In all of the views, like parts are designated by the same reference characters.

The awning is composed of a shade 1, which has one end attached to a spring 45 roller 2, and the other end to a slat 3, in the same manner as described in my co-pending application above referred to. The spring roller is supported upon spreaders 4-4. The spreaders are each formed of a 50 side bar, as shown, and their free ends are connected to a cross bar 5. This latter preferably has strengthening angles 6, 6, at the junction of the side bars and cross bar,—a structure which greatly stiffens the spreaders when the awning is subjected to side strains by the action of the wind.

A halyard 7 is connected to the bar 5, by means of an arm 8, rigidly secured to the bar, which keeps the halyard out of contact with the shade when the spreaders are being 60 raised. The inner ends of the spreaders are pivoted to sliders 9, 9, one on each fly-rod 20. Each slider is preferably made of the shape shown, of sheet metal bent to tubular form so as to encircle the fly-rods and slide 65 freely thereon. Each slider has three pairs of ears, as shown. The lowest pair, 10, 10, are connected together by a pin 11. This pin also serves to support the spreaders when in the horizontal position (see Fig. 2). 70 The pivot for the spreader is supported by these ears. The intermediate ears 12, 12, are connected together by a pin, which serves as an axle for the roller 13. The roller is preferably made of fiber or some 75 other substance which will be noiseless and yielding. It serves two functions. The first is to reduce friction, and at the same time prevent rattling of the sliders on the fly-rods. The second is to serve as a stop 80 for engagement with the spreaders when raised thus reducing shocks and noise. The upper pair of ears 14, 14, support one end of a roller or bar 15. This latter roller extends from one slide to the other, and lies 85 outside of and guides the shade. Its purpose is to hold that part of the shade lying beneath it close to the window opening, as shown.

The end of the shade carrying the slat 3 90 is raised by means of a halyard 16. The two halyards 7 and 16 pass through blocks 17 and 18, and are secured to a cleat 19. The fly-rods 20, 20 preferably extend from the lower part of the window opening to the 95 top, and the ends are supported by brackets 21, 21, as shown.

The operation of the device is very similar to that described in my co-pending application for patent. The awning is spread by 100 slackening the halyard 7 and hauling in on the halyard 16. The lower half of the awning is furled by hauling in on the halyard 7, thus raising the spreaders and allowing the spring roller to take up the shade. 105 The upper half is furled by slackening the halyard 16 to allow the spring roller to take up that portion of the shade. The entire awning when furled may be raised to the upper part of the window by hauling in on 110 the halyards 7, which action elevates the bar 5, spreaders 4, 4, and sliders 9, 9, the latter

sliding upward on the fly-rods 20, 20. The arm 8 allows the halyard 7 a clear pull, free of contact with the shade. The roller 15 will rotate when the shade is raised or lowered in contact with it.

For wider awnings than that shown in Figs. 1 and 2, I may employ a plurality of halyards for lifting the spreaders. This is shown in Fig. 7, where two halyards 7 and 10 7^a are employed. Each is secured to an arm 8 and 8^a, in the same manner and for the same purpose as already described.

For the purpose of initially moving the spreaders from the upright or folded position, due to failure of the halyards to rend freely through the blocks, causing swelling of the rope, I employ the device illustrated in Figs. 8 and 9. A leaf spring 22 is secured to the underside of the spreader and its free extremity engages with the ears 10, 10. The extremity of the spring is widened as shown in Fig. 9, so that it engages both ears 10, 10. When the spreader is elevated, the spring is expanded or distorted, exerting stress upon the ears 10, 10, and tending to force the spreader outward. When the halyard 7 is released, the spreader will automatically move outward, even if the halyard does not rend freely through the blocks. This spring may be duplicated on each spreader, if desired.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:

1. An awning having a shade; a slat for one end and a spring roller for the other; spreaders supporting the spring roller; fly-rods; sliders on the fly-rods; connections between the spreaders and fly-rods; an intermediate roller or bar connecting the sliders and engaging with the outer side of the shade; and means for raising the sliders.

2. An awning having a shade; a spring roller therefor; spreaders supporting the roller; fly-rods; sliders on the fly-rods; ears on the sliders; a pivot for a spreader between the ears; and a pin connecting the ears and supporting the spreader when lowered.

3. An awning having a shade; a spring roller for the shade; spreaders supporting the spring roller; fly-rods; a slider on each fly-rod; a pivotal connection on each slider for a spreader at the lower part of the

slider; and a roller on the slider intermediate its ends, said roller engaging with the fly-rod and serving as a stop for the spreader when raised.

4. An awning having a shade; a spring roller for the shade; spreaders carrying the spring roller; fly-rods; a slider on each fly-rod, said sliders being made of sheet metal, each with a plurality of opposed ears, the lowermost ears supporting the spreaders; a friction roller supported by the intermediate ears; and a roller supported by the upper ears and engaging with the outside of the shade.

5. An awning having a shade; a spring roller for the shade; a spreader carrying the spring roller; fly-rods; connections between the spreader and the fly-rods, the spreader being composed of side bars and a cross bar, with an angle at the junction of the side bars and a cross bar.

6. An awning having a shade; a spring roller for the shade; a spreader carrying the spring roller; fly-rods; connections between the fly-rods and the spreader; an intermediate roller engaging with the outer side of the shade; an arm on the spreader; and halyards connected to the arm and leading upward.

7. An awning having a shade; a slat for one end and a spring roller for the other; spreaders supporting the spring roller; fly-rods; sliders on the fly-rods; a pivot for the spreader adjacent to the bottom of a slider; a roller or bar connecting the sliders, adjacent to their upper ends and extending across the shade; and an intermediate cushioning roller carried by the slider and adapted to engage with the fly-rod and also to be engaged by the spreader when the latter is elevated.

8. An awning having a shade; a spring roller therefor; spreaders supporting the roller; fly-rods; sliders on the fly-rods; a pivot for the spreader at each slider; and a spring normally distorted when the fly-rod is elevated; and a halyard for raising the spreaders.

9. An awning having a shade; a spring roller therefor; spreaders supporting the roller; fly-rods; sliders on each fly-rod, each slider having two opposed ears between which the spreader is pivoted; a leaf spring carried by the spreader, and engaging with the ears; and a halyard for raising the spreaders.

This specification signed and witnessed this 31st day of January, 1913.
